UNITED STATES PATENT OFFICE.

MARGARETH VOLKE, OF BOVEY, MINNESOTA.

DESIGN FOR AN APRON.

44,046.

Specification for Design.

Patented May 13, 1913.

Application filed January 27, 1913. Serial No. 744,581. Term of patent 7 years.

To all whom it may concern:

Be it known that I, MARGARETH VOLKE, a citizen of the United States, residing at Bovey, in the county of Itasca and State of Minnesota, have invented a new, original, and ornamental Design for an Apron, of which the following is a specification, reference being had to the accompanying drawing, forming part thereof.

The figure is a plan view of an apron showing my new design.

I claim:

The ornamental design for an apron, as shown.

MARGARETH VOLKE.

Witnesses:

E. H. BITHER,
L. D. LAMMON.
